DESIGN FOR A GUARD FOR KNITTING OR CROCHET NEEDLES

Jessie Sachs, New York, N. Y.

Application September 11, 1941, Serial No. 103,287

Term of patent 3½ years

To all whom it may concern:

Be it known that I, Jessie Sachs, a citizen of the United States, residing at New York city, in the county of New York and State of New York, have invented a new, original, and ornamental Design for a Guard for Knitting or Crochet Needles, of which the following is a specification, reference being had to the accompanying drawing, forming part thereof.

In the drawing:

Fig. 1 is a side view in elevation of a guard for knitting or crochet needles, showing my new design; and

Fig. 2 is a sectional view thereof taken on line 2—2 of Fig. 1.

I claim:

The ornamental design for a guard for knitting or crochet needles, as shown.

JESSIE SACHS.
